2 Claims. (Cl. 92—7)

1

Digestion of wood or similar fibrous materials to cellulose, or for converting wood into sugar, is effected at an increased pressure and at an elevated temperature, 130° to 180° C. or higher, according as the digestion is carried out according to the bisulphite process, the sulphate process, the sulphurous acid process, or some other process. In practice, processes of digestion of this kind are exclusively carried out periodically, that is to say, the digestion is effected batch-wise, a digester being filled with the raw material, such as wood chips, after which the filling opening is closed and the digester liquor is admitted, and the temperature and pressure are then "run up" in accordance with curves gained from experience, the pressure being determined by the pressure of the steam plus the partial pressure of the gases developed. During the running up and digestion period the cook is usually "gassed off," either in order to keep the pressure down, by discharge of air and SO₂, or in order to recover certain by-products, such as turpentine.

Many attempts have been made to solve the problem of continuous digestion which would consist in continuously feeding the raw material, such as wood chips, into one end of the apparatus used for the digestion, and causing such raw material to move through said apparatus while admitting the digester liquor, steam, and so forth, and finally discharging the material from the other end of the apparatus in the form of "pulp," that is to say, a completely digested product. Methods and apparatuses of the most various kinds have been proposed and tested, but so far no fully tried-out and generally accepted solution of the problem has come forth which has been put in practice on a commercial scale.

Among the problems which must be solved in order to effect a continuous digestion, the following may be noted:

A. The continuous feeding of the raw material, such as wood chips, into the apparatus against a high pressure.

B. A satisfactory impregnation of the raw material with the digester liquor in conjunction with heating of the raw material as well as of the digester liquor.

C. Feeding of the raw material through the apparatus in such manner that control is had of the movement of the mass and of the digester liquor with relation not only to the apparatus but also with relation one to the other, and in such manner that full control is had of the distribution of pressure and temperature, or in other words, of the process of digestion itself.

2

D. The discharge of the digested product.

Heretofore practically all proposed solutions of the problem were based on the same basic principle as that applied to ordinary periodic digesters, namely that the pressure in the digester is determined by the steam pressure corresponding to the digesting temperature plus the partial pressure of the gases present.

It has been found in practice that if the temperature of the digester liquor is at the vaporizing point, the liquor has a pronounced tendency to "travel" relatively to the mass towards the discharge point. This phenomenon is well known from the "blowing" of ordinary digesters, where there is risk of the liquor "going first," while the mass or pulp remains behind and must be washed out of the digester or pried out with the use of crowbars or the like.

This phenomenon is the reason why practically all attempts hitherto made of performing a continuous digestion have failed.

The abovementioned difficulty can be avoided by feeding the wood chips into the bottom of the digester and discharging the digested pulp and the liquor over a discharge lip at the top of the digester, so that the digester always remains filled up to its top.

But this solution of the problem suffers from certain disadvantages, and it is desirable, therefore, to solve the problem in such manner that the material is charged into the top of a vertical digester and the completed product is discharged from the bottom of the digester. This will be evident from the following considerations upon which the present invention is based:

1. For practical reasons the digester should be vertical with its inlet at the top and the discharge at the bottom. In the first place, the material or mass which is specifically heavier, is most easily fed downwards. In the second place, the feeding apparatus when placed at the top of the digester, is more easily accessible for inspection and repair, than if it is placed at the bottom of the digester. In the third place, the digester is most easily emptied if the discharge is effected from the bottom of the same.

2. In accordance with the experience gained from periodic digestion, the material should pass through zones having different temperatures, substantially in such manner that the material first passes through a comparatively cold zone for the purpose of impregnation, and then through the digestion zone proper at full digestion temperature, and finally through a somewhat colder discharge zone. Gas which is possibly separated

during the heating period in the digestion zone, such as SO_2 in the bisulphite process, will attempt to move upward, and if the mass moves downward, the gas will flow in counter-current to the material, which is thus subjected to a gradual pre-heating. Simultaneously the upward flowing gas, such as SO_2 , will successively encounter gradually colder material, so that the gas is again dissolved and thus aids to effect the impregnation.

3. The supply of chemicals—boiling liquor—should be effected exclusively with regard to the predetermined quantity and strength, quite irrespective of the pressure in the digester.

4. The movement of the material and of the digester liquor through the digester should be positively controlled and must not be dependent upon accidents or chances. In other words, and with reference to the phenomenon above mentioned, this means that the flow of the liquor must be brought under absolute control and that its tendency to "travel" relatively to the material must be eliminated. The flow of the liquor through the digester must be determined exclusively by the quantity of liquor introduced in the digester.

From the considerations above stated it is evident that a primary condition for the process proceeding according to the lines above stated, is that the digester must be completely "dead," that is to say, completely filled with liquor, without any steam space at the top. If the liquor is at the vaporization temperature, the steam pressure constitutes the force that causes the tendency of the liquor to "travel." This cause must be eliminated in the first place.

The conclusion is that the digester must be maintained under compression, that is to say, the liquor therein must be under a pressure which exceeds the steam pressure of the digester liquor at the maximum digestion temperature reached. This pressure of the liquor may conveniently be identical to a pump pressure which is determined by the aid of a pressure regulator.

It will easily be understood that the digester being maintained under compression by the aid of a pump pressure, the condition above stated under point 2 can also be fulfilled, since in such case there is no obstacle to maintaining different temperatures in different zones, as long as the vaporization temperature at the prevailing pressure is not reached at any point. There is thus also nothing to prevent a cooler impregnating zone being maintained at the top of the digester and a hotter digesting zone at a lower level, in accordance with point 2.

It will be understood from point 3 that the treating liquor itself must not be used as a compression liquid. This is for the reason that the first-named liquor must be controlled in such manner that a predetermined quantity thereof is introduced into the digester, but the last-named liquid must be so controlled that a predetermined pressure is maintained.

It will be understood from point 4 that the compression liquid must not be introduced in the digester at such a point that a variation of the quantity introduced influences the course of the process of digestion. The conclusion is that the compression liquid should be introduced at the bottom of the digester in conjunction with the discharge, where the said liquid has no influence whatever on the course of the digestion itself, whether qualitatively or quantitatively.

The quantity of compression liquid introduced, which in itself is of subordinate importance, be-

comes automatically equal to the difference between the quantity of the entire discharge and the sum of the quantities charged into the digester of raw material, liquor, including chemicals, and steam possibly introduced.

By varying the discharge quantity in a suitable manner it is thus possible to introduce a suitable quantity of compression liquid.

As regards the compression liquid itself, the 10 only possibility that presents itself in practice is to use waste liquor, or so-called black liquor, in order not to lower the content of chemicals and dissolved substance in the liquor that is conducted to the liquor recovery. For economical reasons it 15 is not possible to use water as compression liquid.

In accordance with the above considerations, the process according to the present invention mainly consists in maintaining the material and the treating liquor during their movement 20 through the digester at a pressure which is higher than the vapor pressure of the treating liquor at the maximum temperature prevailing in the digester, by pumping a compression liquid into the digester independently of the charging of raw 25 material and treating liquor into said digester. As a compression liquid, waste liquor or so-called black liquor may preferably be used. It is suitable to introduce the compression liquid at the discharge end of the digester, so that said liquid 30 simultaneously serves to dilute and to effect discharge of the digested product.

The present process and an apparatus for performing the same are illustrated diagrammatically and by way of example in the accompanying 35 drawing.

Raw material is continuously supplied to the vertical digester 1 from the chip receptacle 2 which is provided with a vibration device 3 for producing a uniform supply of chips to a measuring apparatus 4, for instance in the form of a conveyor screw having a controllable speed, a blade wheel, a shaking apparatus, or some similar well-known apparatus. Since the digester is assumed to be under a pressure which is higher than the 45 vapor pressure of the digester liquor at the digestion temperature used, the digester must be completely filled with liquor. The feeding of the raw material, such as wood chips, into this liquor-filled space under pressure is illustrated in the 50 drawing as effected by means of a combination of a rotating cell wheel 5, a sieve 6 in a sieve housing provided at the top of the digester and surrounding a feeding screw 7, a circulation pump 8, and conduits connecting the cell wheel, the sieve housing, and the pump.

The feeding is effected in the following manner: An empty cell in the cell wheel is partly filled with chips at 11 and continues to rotate in the direction of the arrow, more liquor entering the 60 cell at 12, for instance by leakage from 13. At 13 the chips are emptied from the cell by the circulating liquor which is pumped by the pump 8 from the sieve 6 through the connection 9 to the cell in question, and is returned from said cell to the inner side of the sieve 6 where the chips brought along are fed downward into the digester by the screws 7, while the liquor is separated through the sieve and is returned in circulation to the cell wheel. The cell continues to rotate after the 65 chips have been emptied from the same, and then carries along liquor which is emptied at 14 into a collecting receptacle 16, or digester liquor tank, from which the liquor is returned to the circulation path, for instance by a pump 15.

At the top of the digester means 10 are provided

for gassing off air, for instance, in a well known manner.

While the chips or other raw material are fed into the digester at the top thereof by means of the screw 7, the impregnation or digester liquor may be supplied, in a manner previously known in itself, either directly to the digester at 28, or at 28a through the receptacle 16 and the pump 15. Fresh liquor, SO_2 or other chemicals, may also be supplied wholly or partially at a later stage, for instance at 28b or at 28c, suitably in connection with a local circulation of the liquor and heating of the same by means of steam, as indicated at 17. In the upper portion of the digester the impregnation of the material takes place at a comparatively low temperature, 60° to 120° C., after which heat is supplied at 17 either directly in the form of steam or indirectly by local circulation of the liquor through a heat exchanger in a manner previously known in itself, for which reason such supply of heat has not been illustrated in the drawing. The digestion temperature may for instance be 140° to 180° C., or even higher. Gases which may be separated due to the heating, will rise upward in counter-current to the material fed into the digester, and will thus produce a certain preheating in the impregnating zone, and, due to the decreasing temperature, the gas will at the same time be dissolved again and take part in the impregnation.

In a similar manner further heat may be supplied at 17a, or if desired, the temperature may be decreased at this point.

The completely digested mass, that is, the mixture of fibres and waste liquor, is discharged from the bottom of the digester, and steam and gases are then allowed to escape at 18 in the usual manner, the liquor being separated at 20, while the ready fibre product is conducted away at 21 to be further treated, and the surplus quantity of liquor is conducted at 19 to the liquor recovery. The discharge may be effected, for instance, by the aid of a scraper device 22 and a sluicing device 23 the capacity of which may be controlled by the aid of an automatic relay 24.

A portion of the liquor separated at 20 is returned by means of the pump 25 and at a sufficient pressure for being introduced at 26 into the bottom of the digester to serve the purpose of diluting the stock or pulp in connection with the discharge of the same. By means of a valve 27 which is inserted in the pump conduit, and which is actuated by the pressure in the digester, the quantity of the compression liquid introduced at 26 is regulated in such manner that the desired compression is maintained in the digester, and consequently, during continuous operation the quantity of liquid pumped in at 26 becomes equal to the difference between the discharge quantity at 23 and the quantities of raw material, digester liquor, and steam introduced at 13, 28, 28b, 28c, 17 and 17a, the discharge quantity at 23 being, of course, greater than the sum of the last mentioned quantities.

By constructing the relay 24 controlling the sluicing device 23 as a temperature relay, the discharge may be caused to take place at a desired predetermined temperature. For instance, if the relay 24 is adjusted for the temperature 120° C., then discharge will take place as long as, owing to the supply at 26 of compression liquid having a temperature of, say, 80° C., the temperature in the digester is decreased from, say, 170° C. to 120° C. at the discharge, and during all this time the supplied quantity of compression liquid is of

course equal to the abovementioned difference between the discharge quantity at 23 and the quantities of raw material, digester liquor, and steam simultaneously fed into the digester. If the temperature at the bottom of the digester tends to fall below 120° C., due, for instance, to the temperature of the supplied compression liquid decreasing, then the temperature relay 24 will reduce the discharge rate at 23, and as a result hereof the quantity of compression liquid supplied at 26 is also reduced through the action of the pressure actuated valve 27, so that the desired temperature of 120° C. is maintained at the bottom of the digester. If, on the other hand, the temperature at the bottom of the digester tends to rise above the said temperature of 120° C. due, for instance, to the temperature of the compression liquid increasing, then the relay 24 will increase the discharge rate at 23, and as a result hereof the relay 27 will also admit more compression liquid at 26, so that the desired temperature of 120° C. is maintained at the bottom of the digester. If another temperature, say 130° C., is desired, then the temperature relay 24 is adjusted 15 for this temperature, and in such case a temperature of 130° C. will be maintained at the bottom of the digester. The capacity of the sluicing device 23 shall of course be so large that said device is always capable of discharging not only the 20 quantities of raw material, digester liquor, and steam introduced at 13, 28, 28b, 28c, 17, and 17a, but also the compression liquid introduced at 26, irrespective of the quantity thereof, and the 25 temperature of this compression liquid must, of course, always be lower than the discharge 30 temperature.

By the simultaneous use of a valve actuated by the pressure in the digester which controls the supply of compression liquid, and a sluicing device 40 which is influenced by the temperature, the entire course of digestion may thus be automatically controlled and regulated.

The process and the apparatus above described may be used, in principle, regardless of whether 45 the treatment is effected with bisulphite, sulphate, SO_2 -water, or some other combination. The supply of chemicals and the supply of heat may be effected in accordance with well known methods which, therefore, need not be further 50 explained.

I claim:

1. The process of continuous digestion of fibrous materials under pressure, which consists in continuously introducing the raw material into 55 an impregnation zone in a vertical digester at the top thereof, said impregnation zone having a temperature substantially below digestion temperature, continuously introducing digester liquor into said impregnation zone in the digester at the 60 top thereof to continuously maintain the digester completely filled with a mixture of raw material and digester liquor, supplying heat to said mixture in a digestion zone below said impregnation zone in said digester, passing said mixture of raw material and digester liquor as a continuous downward flow through the digester from the top to the bottom thereof, continuously discharging the digested product from the bottom of said digester, maintaining said mixture of material and digester 65 liquor during such flow through the digester under a pressure higher than the vaporization pressure of the digester liquor at the maximum temperature prevailing in the digester, thereby preventing generation of vapour from said digester liquor, controlling such pressure by introducing 70 75

into the digester in the vicinity of the bottom thereof and independently of the supply of raw material and digester liquor into the digester at the top thereof a compression liquid consisting of waste liquor having a lower temperature than the digestion temperature in the digester, such compression liquid producing a decrease in temperature at the bottom of the digester, the quantity of compression liquid introduced equalling the difference between the quantity discharged and the sum of the quantities charged into the digester per unit of time, and controlling the rate of discharge from the digester in dependence upon the temperature at the bottom of the digester, thereby effecting regulation of the quantity of compression liquid introduced in the digester whereby a predetermined temperature is maintained at the bottom of the digester.

2. Apparatus for continuous digestion of fibrous materials, comprising in combination a vertical digester, means for continuously introducing raw material into said digester at the top end thereof, means for continuously introducing digester liquor into said digester at the top end thereof, means for heating the fibrous material and digester liquor in said digester intermediate the top and bottom ends thereof, means for continuously discharging digested product from the bottom end of said digester, a conduit connected to said digester in the vicinity of the bottom end thereof for introducing a compression liquid in the digester at the bottom end, means in said conduit actuated by the pressure in said digester for controlling the flow of compression liquid through said conduit so as to maintain a predetermined pressure in said digester, a discharging apparatus having a variable capacity associated

5 with the bottom end of said digester for continuously discharging digested product therefrom, and an adjustable temperature relay actuated by the temperature at the bottom end of the digester and operatively connected to said discharge apparatus so as to control the operation of said apparatus in response to the temperature at the bottom end of the digester.
